UNITED STATES PATENT OFFICE

122,630

DESIGN FOR A MOP

Paul M. Rogers, Orange, Calif.

Application July 30, 1940, Serial No. 94,048

Term of patent 14 years

To all whom it may concern:

Be it known that I, Paul M. Rogers, a citizen of the United States, residing at Orange, in the county of Orange and State of California, have invented a new, original, and ornamental Design for a Mop, of which the following is a specification, reference being had to the accompanying drawing, forming part thereof.

Figure 1 is a front elevational view of a mop showing my new design;

Figure 2 is a sectional view on the line 2—2 of Fig. 1 on a slightly enlarged scale; and

Figure 3 is a fragmentary detailed view, on a slightly enlarged scale, of a portion of the mop illustrated in Figures 1 and 2.

I claim:

The ornamental design for a mop, substantially as shown.

PAUL M. ROGERS.
